A. H. OSTRANDER

TANK HEATER AND WATER CIRCULATOR

Filed Dec. 6, 1921

Inventor
Albert H. Ostrander

by Drury & Hague, Atty's.

UNITED STATES PATENT OFFICE.

ALBERT H. OSTRANDER, OF PANORA, IOWA.

TANK HEATER AND WATER CIRCULATOR.

Application filed December 6, 1921. Serial No. 520,339.

To all whom it may concern:

Be it known that I, ALBERT H. OSTRANDER, a citizen of the United States, and resident of Panora, in the county of Guthrie and State of Iowa, have invented a certain new and useful Tank Heater and Water Circulator, of which the following is a specification.

The object of my invention is to provide 10 a tank heater and water circulating device of simple, durable and inexpensive construction which may be easily and quickly placed into position in a stock watering tank, and when so applied will efficiently and uniformly heat the water within the tank.

A further object is to provide in connection with that type of tank heaters which is adapted to be placed inside of an open stock watering tank for the purpose of preventing 20 the water from freezing, new and improved means for causing the water adjacent to the outer walls of the tank to circulate in such a manner that it will not freeze to said walls.

25 A further object is to provide a tank heater adapted to burn liquid fuel and so arranged that the temperature of the heater may be accurately and easily obtained while in position in the tank.

30 These and other objects will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

35 Figure 1 is a plan view of a stock watering tank showing the manner in which my improved heating device is mounted therein, the said heating device having a portion of its top broken away to show the interior construction.

40 Figure 2 is a vertical longitudinal sectional view of my improved heater.

Figure 3 is a transverse, sectional view taken on the line 3-3 of Figure 2.

45 Figure 4 is a detail view of the oil burner used in connection with my improved heater.

50 Figure 5 is a detail view of one end of the heating coil showing the manner in which it is secured to the body portion of the heater.

Figure 6 is a detail sectional view taken on the line 6-6 of Figure 1.

The numeral 10 indicates the bottom of an ordinary stock watering tank having a cylindrical and vertically arranged wall 11, 60 which is illustrated for the purpose of showing the manner in which my improved heater is applied.

My improved heater comprises a substantially rectangular body portion 12 having 65 side members 13, a top member 14, a bottom member 15 and one end member 16.

The end member 16 is provided with a centrally arranged opening 17. An elbow 18 is secured to the end member 16 so as 70 to register with an opening 17, by means of suitable rivets or bolts 19, and is secured in such a manner that a water tight joint is formed between said elbow and said end plate.

The upper end of the elbow 18 is provided with an upwardly extending pipe 20 of such length that its upper end will extend above the water level within the tank, the level of the water being indicated by 80 the line 21, in Figure 2.

The pipe 20 forms a sort of chimney for removing the products of combustion from the burner, to be described.

The opposite end of the body portion 85 from the plate 16 is provided with flanges or lugs 22 for the purpose of securing one end of an inclined draft pipe 23 in position adjacent thereto by means of rivets or bolts 24.

This pipe 23 is of such length that its upper end will extend a considerable distance above the water line 21.

The lower end of the pipe 23 and the front end of the body portion 12 should be joined together so as to form a water tight joint to prevent water from entering the said body portion.

Secured in the front end of the body portion 12, I have provided a plate 25 which 100 is provided with an upper vertical portion and a horizontally arranged and rearwardly extending portion 26, and a downwardly extending portion 27 adjacent to the front edge of the member 26.

The lower edge of the member 27 is provided with a forwardly extending portion 28 which serves as a base to support the member 25, the member 25 being so arranged that it may be removed from the body por- 110

tion by moving it rearwardly, then tipping its upper end forwardly, after which it may be removed through the tube 23.

The said member 25 is designed to fit the walls of the member 12 so as to be substantially air tight.

The member 25 is provided with an opening 29 for the purpose of providing means through which the burner may be lighted.

10 A damper 30 is pivotally connected to the plate 25 in such a manner that it will swing to position to close the opening 29.

Secured upon the member 26, I have provided a body portion 31 of a burner, which 15 body portion comprises substantially a pipe T having each end closed by means of plugs 32, one of the plugs 32 being designed to receive one end of a fuel supply pipe 33 which extends rearwardly, thence curved 20 upwardly and forwardly and passes through an opening in the plate 25, and upwardly through the tube 23 having its upper portion secured to the top of the tube by means of a clamp 34. The upper end of the pipe 25 33 is provided with a pet cock 35 mounted in the bottom of a supply tank 36, the tank 36 being secured to the upper forward edge of the tube 23. The curved portion of 30 the lower end of the tube 33 is secured in position by means of braces 37 secured to the plate 26.

35 A burner cap 38 is secured in the upwardly extending opening of the T 31 and designed to rest immediately below the forwardly extending portion of the curved portion 33 so that the fuel may be heated and vaporized before it enters the chamber of the member 31. Air is admitted to the burner through an opening 39 in the 40 plate 26.

45 By the construction just described, it will be seen that I have provided a burner which will supply heat to the interior of the body portion 12 and will heat the water surrounding the said body portion in substantially the same manner as has heretofore been employed in similar tank heaters, but considerable difficulty has been experienced in heaters of this class due to the fact that 50 the heater is generally set near the center of the tank and central portion of the water within the tank becomes heated and the ice above the heater will be thawed, but the ice will be permitted to form on the inner face of the wall 11 and over the top of the outside edges of the top of the water. These tanks are usually of considerable diameter and the stock drink from the outer edge of the tank which is usually frozen over to such a distance that the stock are 55 unable to reach the thawed portion in the center.

60 To overcome this difficulty, I have provided means for circulating the water within the tank in such a manner that the walls

of the tank will receive a portion of the heated water, and thereby prevent ice from forming.

For accomplishing this purpose, I have provided a heating coil 39^a within the body portion 12. This coil comprises a pipe having one end extending through one of the side members 13 near the front and the bottom thereof. This pipe thence bends upwardly and forwardly to a point above the burner member 38. The pipe is then bent into a series of S's and has its opposite end extending through the opposite plate 13 near its upper and rear edges. The manner in which the ends of the pipe are secured in the plate 13 is clearly shown in Figure 5. A lock washer 40 is screwed on the end of the pipe and designed to rest adjacent to the inner face of the plate 13.

55 An elastic washer 41 is provided for the outside of the plate 13 and held in position by means of a lock washer 42. This provides means for rigidly securing both ends of the coil 39^a into its respective side plate 13.

90 By removing the lock washer 42 and then tilting the coil 39^a with one of its side edges upward and the other one downward, the ends of the coil 39^a may be drawn in through the openings, after which the coil 39^a may be removed through the front end of the body portion.

95 I have arranged a number of deflector plates 43 which are secured to the transversely arranged portions of the coil 39^a in such a manner that the heat from the burner 38 may move through the body portion 12 in a zig zag manner until it reaches the outlet pipe 20.

100 Secured to the outwardly extending portion of the rear end of the coil 39^a, I have provided a pipe 44 having the shape of a semi-circle, and of such diameter that its free end will lie parallel with the wall 11 and comparatively close thereto. The said outer end should extend slightly upwardly from its fixed end, the said outer end being supported by means of legs 45, shown in detail in Figure 6.

105 By this arrangement, it will be seen that if the body portion 12 is placed in the tank as shown in Figure 1, and the fuel from the burner 18 is ignited, the interior of the body portion 12 will become heated, and also the 110 coil 39^a.

115 The heating of the coil 39^a will cause the water to enter the lower end of the coil 39^a and be discharged through the outer end of the pipe 44 in such a manner that the 120 current of water will be caused to circulate adjacent to the wall 11 of the tank and in an anti-clockwise direction, as shown in Figure 1.

125 The body portion of the heater member 12 will extend substantially transversely in

the path of travel of the current, and thereby cause a large portion of the cold water from the wall 11 to engage the said heated body portion, and become heated.

6 By this arrangement, I have found that a very uniform temperature may be obtained throughout the tank with a comparatively small fuel consumption, as all of the heat from the burner is applied to the cooler 10 water which prevents it from freezing while with the ordinary burner, the heated water rises to the top and center of the tank, and a large portion of the heat of which is radiated to the outside atmosphere above 15 the water in the tank.

It will also be seen that the temperature may be regulated by controlling the valve 20 35, and that the burner may be easily and quickly removed for cleaning or repairing 25 when necessary, and also the heating coil may be easily and quickly removed.

It will, therefore, be seen that I have provided a tank heater and water circulating device of simple, durable and inexpensive 25 30 construction which may be easily and quickly installed or removed from the tank when it is desired, and which will very efficiently and uniformly heat the water within the tank when in operation.

30 I claim as my invention:

1. The combination of a tank with a water heater having a body portion of substantially a rectangular shape and arranged with its longitudinal axis radial within the tank, 35 means for supplying heat to the interior of the body portion, a circulating coil within said body portion having each of its ends communicating with the water within the tank and surrounding said body portion, the discharge end of said coil being provided with a curved pipe having its discharge at the opposite side of the tank from which the body portion is mounted, and in such a manner that water being discharged from 40 45 said pipe will flow in a circular manner adjacent to the wall of said tank, and cause the water within the tank to travel transversely over the said body portion.

2. A heater for stock watering tanks comprising a substantially rectangular body portion having a bottom, top and side walls and one end wall provided with an opening, an elbow secured to said end wall in communication with said opening, an upwardly 50 55 extending discharge pipe in communication

with said elbow, a draft pipe secured to the opposite end of said body portion extending upwardly and forwardly, a detachable plate in the forward end of said body portion, a burner secured to the inner face of said plate, a supply tank on the upper end of said draft pipe, a pipe communicating with said supply tank and said burner, a heating coil above said burner and within said body portion having one end communicating with the outside of said body portion near its lower side, and its opposite end communicating with the exterior of said body portion near its top side, a circulating tube in communication with the upper end of said heating coil, and means for supporting the outer end of said tube.

3. A tank heater comprising a hollow body portion designed to be entirely submerged in liquid, means for supplying heat to the interior of said body portion, a coil detachably secured to the interior of said body portion and having its ends in communication with the liquid surrounding the outside of said body portion, an auxiliary 75 80 circulating coil secured to the discharge end of said heating coil having its discharge end so arranged that the liquid in which the heater is submerged will be moved in a circular path in such a manner as to travel over 85 the said body portion while in movement.

4. A tank heater comprising a hollow body portion designed to be entirely submerged in liquid, detachable means for supporting a burner within said body portion, upwardly extending means for supplying air to said burner having its upper end extending above the liquid level, a second pipe in communication with said body portion for removing the products of combustion 90 95 from said burner having its upper end above the liquid level, a fuel tank mounted on the upper end of said supply pipe, a pipe in communication with said fuel tank extending downwardly through said air supply pipe and communicating with said burner, a heating coil detachably secured within said body portion above said burner having its ends in communication with the liquid surrounding said body portion, an auxiliary 100 105 circulating pipe in communication with the discharge end of said heating coil, and deflector plates secured to said heating coil.

Des Moines, Iowa, October 19, 1921.

ALBERT H. OSTRANDER.
